US00D462332S

(12) United States Design Patent (10) Patent No.: US D462,332 S
Mayo et al. (45) Date of Patent:  Sep. 3, 2002

(54) INFRARED HAND-HELD REMOTE CONTROL

D382,271 S * 8/1997 Akwiwu D14/218
D432,525 S * 10/2000 Beecroft D14/218

* cited by examiner

(75) Inventors: Noel Mayo, Philadelphia; Joel S. Spira, Coopersburg; Jason Killo, Emmaus, all of PA (US)

Primary Examiner—Ted Shooman

Assistant Examiner—Selina Sikder

(74) Attorney, Agent, or Firm—Ostrolenk, Faber, Gerb & Soffen, LLP

(73) Assignee: Lutron Electronics, Co., Inc., PA (US)

() Term: 14 Years

(21) Appl. No.: 29/141,438

(22) Filed: May 7, 2001

(51) LOC (7) Cl. 13-03

(52) U.S. Cl. D13/168

(58) Field of Search D13/158, 159, D13/160, 162, 164, 168, 174, 177; D14/218; 200/331; 348/734; 455/151.1–151.4, 352–355

FIG. 1 Is a perspective of the infrared hand-held remote control of the present invention.

FIG. 2 is a front view of the infrared hand-held remote control of the present invention.

FIG. 3 is a rear view of the infrared hand-held remote control of the present invention.

FIG. 4 is a top view (partially in perspective) of the infrared hand-held remote control of the present invention

FIG. 5 is a bottom view of the infrared hand-held remote control of the present invention.

FIG. 6 is a left-side view (partially in perspective) of the infrared hand-held remote control of the present invention; and,

FIG. 7 is a right-side view (partially in perspective) of the infrared hand-held remote control of the present invention.
